METHOD AND APPARATUS FOR FORMING
A RAISED CHARACTER OF RADIUM LU-
MINOUS MATERIAL OR THE LIKE

Howard L. Page, Chicago, Ill.

Application December 9, 1930, Serial No. 501,156

16 Claims. (Cl. 101—114)

This invention relates to methods and means for applying indicia to a receiving surface, and with particularity to a method whereby such indicia may be applied without requiring any close physical or personal contact with the material constituting the indicia.

While the invention disclosed herein relates to a process which is capable of use in any connection where characters or indicia are to be transferred or applied to a receiving surface, the invention is of outstanding value in the field of radium luminescent products. For example, in the case of articles that are required to be coated with radium luminescent compounds and/or mixtures, it is highly desirable that the operation of applying luminescent compounds be effected without necessitating the operator handling or being in close contact with the radium bearing material. The means and process according to this invention enable radium bearing or other similar materials to be applied to a receiving surface with a minimum of danger to the operator. In the case of radium luminescent materials it has been found, as a matter of fact, that in order that the self-luminescent material, for example zinc sulphide, may retain its efficiency as a self-luminescent source, it is highly desirable that this material which is usually crystalline be subjected to no excessive pressures or mechanical contacts. For example in the known methods of mixing so-called radium luminescent paint, using zinc sulphide or the like, it is necessary to agitate the crystals of the zinc sulphide in the liquid carrier in order to insure the proper relation or consistency of the mixture since the crystals, because of their comparative heaviness, usually tend to separate out or settle. The usual method heretofore employed has required the operator to stir manually the mixture or paint at very frequent intervals. This of course requires very close contact with the material, and at the same time, unless the material is stirred at regular intervals the desired consistency and/or uniformity of the paint is not attained.

Accordingly it is one of the principal objects of this invention to provide a method of applying paints, such as radium luminescent paints, to a receiving surface whereby the person controlling the application is not required to come into close physical contact with the paint.

Another ancillary object is the provision of a method whereby the luminous paints may be applied with a maximum uniformity.

55 Another object of the invention is to provide a

method of transferring indicia material to a final receiving surface wherein the said material is initially wet, but is allowed to dry prior to the actual transfer thereof to the receiving surface.

Another object of the invention is to provide a 60 method for automatically applying radium luminescent paints or the like to an indicia transfer member.

A feature of the invention relates to a method of transferring indicia from a carrier to a final 65 receiving surface wherein the indicia material is allowed to dry in a mold and the final receiving surface is provided with a portion of its surface covered with an adhesive which acts to extract the indicia material from the mold, said adhesive 70 also serving to fasten the transfer indicia to the final receiving surface.

A still further feature relates to methods and means for manipulating radium luminescent paints in their application to a final receiving surface, such as a dial or the like.

Another object is to provide a system of this kind, in which the mold for the characters is formed of a substance which is able to hold the fluid or semi-fluid paste until it is dry, and which 80 does not adhere to the characters formed of the paste after the paste has solidified to form such characters. Suitable materials for forming the mold are wax or a mixture of waxes with a suitable solid material to give added toughness.

Another object is to provide a machine for this purpose, in which the semi-fluid mixture or paste is agitated before it is fed to the mold. Such agitation tends to maintain the paste in proper condition until it is deposited in the mold.

Another object is to furnish an apparatus wherein the paste in passing from a feed cylinder to the mold, travels through a resilient tube which acts as a wiper to smoothly distribute the paste in the cavities of the mold.

95 A further object is to provide a machine of this type, in which the resilient paste conducting tube cooperates with special jaws which function to collapse the tube, and thereby close the same, and to also smooth the paste into the cavities of the 100 mold.

A still further object is to provide a machine of this kind, in which a single lever is used to control all of the operations.

Another object is to provide novel means for 105 printing with an adhesive on a final support, and for then using such adhesive to withdraw the characters from the mold, and to attach such characters to the final support.

With the foregoing objects outlined and with 110

other objects in view which will appear as the description proceeds, the invention consists in the novel features hereinafter described in detail, illustrated in the accompanying drawings, and 5 more particularly pointed out in the appended claims.

In the drawings,

Fig. 1 is a front elevation of my improved machine.

10 Fig. 2 is a side elevation of the same.

Fig. 3 is a horizontal sectional view of a detail on the line 3—3 of Fig. 2.

Fig. 4 is a sectional view of a detail on the line 4—4 of Fig. 3.

15 Fig. 5 is a sectional view of a detail on the line 5—5 of Fig. 3.

Fig. 6 is a similar view on the line 6—6 of Fig. 3.

20 Fig. 7 is a front elevation of the auxiliary apparatus for withdrawing the formed characters from the mold, and for applying them to the final support.

Fig. 8 is a sectional view on the line 8—8 of Fig. 7.

25 Referring to Figs. 1 to 6 inclusive, 1 is a refillable hollow cylinder to hold the paste from which the characters are formed. This cylinder is rigidly mounted on a vertical turn-table 2, and it has a spout 2a through which the paste is ejected. The cylinder is secured to the turn-table or wheel 30 2 by means of a fixed jaw 3, and a hinge jaw 4, the latter, being pressed toward the stationary jaw by means of a coiled spring 5, so that the cylinder may be readily removed when empty.

35 Within the cylinder, there is a piston 1a fastened to the lower end of a rack 6 which meshes with a pinion 7 that is secured to the outer end of a shaft 8 (Fig. 3) which rotates in a bearing 9 that is fast on the wheel 2.

40 Shaft 8 has threaded to it at 8a a non-magnetic shaft 10 which has a slot and key connection, as shown at 10a with a brass shell 12 which is rigidly secured to an iron cap 13. A leaf spring 14 that is secured to the rear side of the plate 2 and engages the shell, acts to yieldingly move 45 the shell and its cap toward the plate 2.

49 Plate 2 carries a similar assembly of parts in cylinder 18 and bearing 15, and a similar brass shell 16 on which is mounted an iron cap 17. The plate is fast on a horizontal shaft 19 which 50 rotates in the arms 20 and 20a of the stationary frame of the machine. Said frame also supports the iron pole piece 21 of a rotatable electro-magnet 22 on one end of which there is mounted insulated contact rings 23 and 24, against which 55 press carbon contacts 25 and 26 that are urged outwardly by springs 27 and 28 that are secured in position by threaded terminals 29 and 30 through which current is led intermittently to said electro-magnet. The portion of the support 60 20 which carries the parts 25 to 30 inclusive, may be made of insulating material, so as not to interfere with the passage of current to the electro-magnet.

65 Electro-magnet 22 is fixed to a rotatable shaft 31 which also supports a loose gear 32 that carries pins 33 and 34 which support planetary gears 35 and 36 that are in mesh with a gear 35a that is fast on the shaft 31. Gears 35 and 36 also mesh 70 with an internal gear 37 that is loosely mounted on the shaft 31 and is fixed to a gear 38. The shaft 31 is continuously rotated by means of a worm gear 39 that is fixed on the shaft and driven by a worm 40.

75 A gear 41, fast on the shaft 19, meshes with the loose gear 32, and a notched disk 42 is fixed to

the shaft 19 and is arranged in alignment with the gear 38. As best shown in Fig. 5, the disk 42 is provided with a pair of diametrically opposite notches 43 and 44. These notches and the teeth of the gear 38 cooperate with a flange 45 on a rockable rod 46 that is pivotally mounted on the machine frame at 47. A spring 46a normally urges the rod toward the disk 42, and it will be understood that when the flange 45 is in engagement with either one of the notches of the disk, the latter will be prevented from rotating, while if the flange engages any tooth of the gear 38, such gear cannot rotate.

80 In operation, the worm 40 continuously drives the worm gear 39, thereby rotating shaft 31, while the flange 45 engages the notch 44 and holds the shaft 19 and plate 2 in such a fixed position that cylinder 1 is in the position shown in Fig. 1. The paste or other material with which the cylinder has been previously filled, may now be forced through the nozzle 2a by completing an electric circuit through magnet 22 which causes iron cap 13 to be drawn into engagement with the pole piece 21, and the contact thus formed, suffices to rotate the gear 7, thereby forcing the 100 rack 6 and its associated piston downwardly, and ejecting paste from the nozzle. Obviously the flow may be stopped by breaking the electric circuit, whereupon spring 14 moves the brass shell 12 away from the pole 21 and disconnects the cap 105 13 from said pole. Upon the completion of this action, rod 46 may be moved in a manner herein-after described to release disk 42 and engage toothed wheel 38, whereupon the gears 35a, 35, 36, 32 and 41 cause shaft 19 to rotate plate 2 one-half a revolution, or until the notch 43 registers with the flange 45, at which time the spring 46a 110 will cause the flange to move into said notch and thereby cause cylinder 18 to halt in the position previously occupied by cylinder 1.

115 This intermittent changing of the positions of cylinders 1 and 18 is important, as it effectually keeps the contents of the cylinders properly mixed.

120 As best shown in Figs. 1 and 2, a resilient tube 49 of rubber or the like is arranged below the nozzle 2a, and is held in place by a bracket 50, this tube extends into and preferably between jaws 51 and 52, which act to squeeze the tube and cut off the flow therefrom. Jaw 51 is an offset 125 on shaft 53, while jaw 52 is an offset on a rockable sleeve 54 in which the shaft 53 may rock. A bevel gear 55 is fixed to the shaft, and a similar gear 56 is fixed to the sleeve, and these parts are 130 all supported by a bearing 57 in which the sleeve 54 rocks. The shaft and sleeve are moved in opposite directions by means of a bevel gear 58 which meshes with the gears 55 and 56, and is fixed to the upper end of a rock shaft 59. The latter is journaled in suitable supports on the frame, and is provided at its lower end with a fixed arm 60 that is connected by a link 61 to a hand operated lever 62. The lever can swing upwardly and downwardly on a pin 63 which projects from a post 64 that is swiveled on a support 65. This construction allows the lever to move upwardly or downwardly, and to swing horizontally.

135 The operating lever has a handle portion 62b which can slide over a support 66 on which is 140 mounted suitably insulated electric contacts 67 and 68. These contacts are connected to the terminals 29 and 30 by means of conducting wires 67a and 68a, and in one of these wires, a battery 68b or the like is interposed. Obviously, 145 150

when the handle bridges the contacts 67 and 68, the electro-magnet 22 will be energized.

As all of the movements of the machine are controlled by the single lever 62, that lever has an upwardly extending portion 62a which supports an elevator 70 that has a key 71 operating in a keyway 72 in a post 73 which projects upwardly from the base 74, of the machine. The elevator or support 70 carries bearings 75 and 76 in which rotates a shaft 77 that carries at one end, a fast pulley 78, which, when the elevator is raised, engages the main drive belt 79, which is driven by any suitable prime mover, (not shown). The belt also drives a main drive pulley 80, fast on a shaft 81 that is journaled in a support 82. This shaft has a fast bevel gear 83 that drives a similar gear 84, fixed on the lower end of a shaft 85, on which the worm 40 is also mounted.

For the purpose of rocking the rod 46, the lower end of the latter is connected by a link 86 to the main operating lever 62, and as shown at 86a, the link is connected to the lever by a lost motion device, so that the lever may swing horizontally for some distance before the link 86 commences to move the rod 46.

Shaft 77 carries also a worm 87 that drives a worm gear 88 that is fixed to a spindle 89 which rotates a horizontal turn-table 90 that is recessed to hold the mold 91.

In operation, an empty mold 91 having in its upper face, cavities or indentations to form the characters such as figures or letters, is placed on the turn-table 90, so as to rotate with the latter. Then the operating lever 62 is raised vertically until the upper surface of the mold is in contact with the under surfaces of the jaws 51 and 52, and the mold is caused to rotate below the jaws by virtue of the friction drive established between pulley 78 and belt 79. Operating lever 62 is then moved toward contacts 67 and 68, and due to the link 61, the gear 58 acts to open the jaws 51 and 52. As the operating lever swings further over the support 66, it will bridge the contacts 67 and 68, and complete the electric circuit, thereby energizing the electro-magnet which is in constant rotation, as it is fixedly mounted on the shaft 31. Consequently, pole piece 21 attracts and firmly holds the iron cap 13, and this results in the turning of the pinion 7 and downward movement of the rack 6, which causes the paste or semi-fluid mixture in the cylinder 1 to flow through the flat tube 49 and fill the recessed portions (Fig. 8) of the mold 91. When the mold is entirely filled, the motion of operating lever 62 is continued in the same direction, past contacts 67 and 68, which results in breaking the electric circuit and stopping the motion of the rack 6. At this point of its travel, operating lever 62, through the previously described linkage, causes plate 2 to rotate until cylinder 18 is in an operative position, thereby completing the cycle of motions. Now, operating lever 62 is slightly raised so as to clear contacts 67 and 68, and is returned to starting position, and this causes the jaws 51 and 52 to close, and the elevator 70 to lower, to provide space for the removal of the full mold and insertion of an empty one.

Among the particular advantages of the machine are—the mixing of the paste or material in both cylinders due to the intermittent rotation, whereby the heavier solid particles are prevented from settling out.

The action of the jaws is of advantage as

they are nearly in contact with the surface of the mold, thereby assisting in preventing the smearing of the paste on the mold.

The action of the lower end of the rubber tube 49 is of advantage, as when it is between the jaws, the flexible material bears against the mold and acts as a wiper on the surface of the mold, thereby cleaning the latter.

The construction of the machine is such as to allow of the placing of molds of different sizes on the turn-table 90.

The spring clips holding cylinders 1 and 18, allow the operator to remove the cylinders and insert refilled ones without delay, and furthermore additional spring clips for holding any number of cylinders may be employed, and these may be filled with pastes of different types or colors, and may be successively used to fill different parts of a single mold. The mold itself is, however, one of the principal features of the invention. In operation, the mold is filled with a mixture or paste which, upon drying, leaves solid characters, and this necessitates a mixture having some adhesive properties. It is manifest that any liquid with such properties will tend to adhere to the mold itself, and it would be very difficult to remove the molded characters from the mold.

I have found that one of the most suitable materials for such a mold is wax. Wax has the unusual feature of not adhering to the adhesive used to compound the paste or semi-fluid mixture, with which the mold is filled, and it also carries an excellent surface polish which materially assists in producing a molded figure having a perfect contour and surface. In forming the mold, the wax is brought in contact with the pattern while in a liquid or plastic condition, and after it cools and solidifies, it may be readily removed from the pattern, and it will have in its face, indentations or cavities corresponding to the projecting portions of the pattern, and in this way, the mold 91 is formed. Such a mold may be used any number of times to produce the finished letters or figures.

While I have found wax to give excellent results, it is evident that the mold might be of a solid nature, such as wood covered with a thin layer of wax, or the mold might be of an alloy of metals which carries or contains sufficient wax or similar material to produce a mold which is capable of holding the paste until the latter hardens, and then readily releases the characters thus formed. In my method, I contemplate using a mold of this character, and it will be evident that such method may be used to unusual advantage in the forming of letters, figures, or other designs from any phosphorescent or radium active compound.

In order to remove the dried characters from the mold, I place the latter, as shown in Figs. 7 and 8, upon one of two stools 92 and 93 that project from a carriage 94 which can travel along a track 95. The stool 93 supports a disk 96 having raised characters 97 thereon which correspond in size and arrangement exactly with the characters 98 which are embedded in the mold. An adhesive substance is applied to the raised characters by means of a suitable roll or the like, and then the carriage is shifted to bring the disk 96 beneath an electro-magnet 99 which is furnished with current in any suitable way. The magnet is supported by a slidable rod 100 which is pivotally connected at 101, to the intermediate portion of an operating lever 102.

102. One end of this lever is pivotally connected at 103 to an arm 104 which is rigidly united with a guide 105 in which the rod slides. The guide is carried by a post 106 which projects upwardly from the base.

5 While the electro-magnet is in the position shown in Fig. 7, a final support 107, such as a metal disk, is placed on its under side, and then, when current is turned into the magnet, this 10 final support will adhere to the electro-magnet. Now, if the lever 102 is operated to depress the final support into engagement with the raised characters 97, the adhesive previously applied to those characters will be transferred to the final 15 support. Then the lever 102 is raised and the carriage is shifted to bring the mold 91 into register with the electro-magnet, and when the lever 102 is depressed, the adhesive on the final support will register with the characters 98 of 20 the mold, and the characters 98 will be caused to adhere to the final support. Then, when the lever 102 is raised, the adhesive will draw the characters 98 out of the mold and afterwards the current may be turned off from the electro- 25 magnet, and the final support with the characters 98 rigidly secured thereto, may be removed from the apparatus.

30 From the foregoing it is believed that my method and apparatus may be readily understood by those skilled in the art, and I am aware that changes may be made in the details disclosed, without departing from the spirit of the invention, as expressed in the claims.

35 What I claim and desire to secure by Letters Patent is:

1. A process comprising mixing a solid with a liquid of an adhesive nature and thereby forming a paste, depositing said paste in a mold having the non-adherent characteristics of wax 40 to form raised characters, and then removing resulting characters from the mold after said paste has dried in the mold, by contacting said characters alone with a member adhesively coated in localized areas corresponding to said characters.

55 2. A process comprising making a paste which at normal temperatures is a liquid, but which is capable of solidifying by drying, depositing the paste in a permanent mold which will not adhere to the paste, and thereby forming withdrawable characters having vertical height, and removing said characters from the mold after the paste has dried, by contacting said characters alone with a member adhesively coated in localized 65 areas corresponding to said characters.

60 3. A process comprising making a paste which is a liquid at normal temperatures but a solid upon drying, depositing said paste in a mold which will not adhere to the paste, allowing the paste to remain in the mold for a sufficient length of time for the paste to solidify and form raised characters, applying adhesive to said characters, and then exerting force upon said adhesive to a final receiving surface in localized 65 areas corresponding to said characters to withdraw the characters from the mold.

70 4. A process including transferring from raised type an adhesive to print corresponding characters on a final support, and then utilizing the adhesive characters to withdraw characters having vertical height from a mold.

75 5. A process comprising introducing a paste which is a liquid at normal temperatures and which solidifies upon drying, into a mold having cavities in the form of characters, imprinting on

80 a final support correspondingly shaped characters with a suitable adhesive, then bringing the printed characters of the final support into contact with the solidified paste of the mold, and then moving the final support and mold away from one another and thereby forming on the final support characters having vertical height.

85 6. In the art of forming and attaching raised indicia to a final receiving surface, the method which includes applying to a recessed transfer surface, material to form the indicia, molding said material in the recesses on said surface, allowing said material to dry in said recesses prior to transfer to said final receiving surface, applying to said final surface an adhesive only at points where the indicia are to be attached, bringing the final receiving surface into contact with the material in the recesses, and withdrawing the receiving surface to lift the said material from said recesses.

90 7. The method according to claim 6, in which the indicia material is applied to the transfer surface in a semi-fluid state.

95 8. The method according to claim 6 in which the said transfer surface is treated prior to the application of the indicia material thereto to prevent said material adhering thereto.

100 9. In the art of forming and attaching to a final receiving surface raised indicia of material containing a radium activated material, the method which comprises automatically applying said material to a recessed transfer surface, molding said material into the desired shape on said surface, allowing said molded material to dry prior to transfer to the final receiving surface, applying to said final surface an adhesive only at 110 points where the indicia are to be attached, bringing the final receiving surface into contact with the material in the recesses, and withdrawing the receiving surface to lift the said material from said recesses.

115 10. In the art of forming and attaching raised indicia to a final receiving surface, the method which includes, the steps of filling a mold having depressions corresponding to the indicia, with a semi-fluid paste, allowing said paste to dry in said 120 depressions prior to applying to a receiving surface, applying to said final surface an adhesive only at points where the indicia are to be attached, bringing the final receiving surface into contact with the material in the depressions, and withdrawing the receiving surface to lift the said material from said depressions.

125 11. The method according to claim 10 in which the paste is liquid at normal temperatures and is dried by evaporation in the depressions.

130 12. The method according to claim 10 in which the paste contains radium luminous material.

135 13. The method according to claim 10 in which the dried paste in the depressions is withdrawn bodily therefrom by an adhesive material.

140 14. In the art of forming and applying raised characters containing radium luminous materials to a final receiving surface, the method which includes the steps of mixing said material with a liquid carrier to form a paste-like adhesive mass, pouring said mass into a mold having depressions corresponding to the indicia, allowing said paste to become solid in said depressions, applying adhesive material to said final surface only at the points where the indicia are to be attached, positioning said surface in contact with the material in the depressions, and moving said final surface to withdraw said material bodily from the depressions.

145 15. In the art of applying raised characters to a

final receiving surface, the method which includes the steps of applying to said receiving surface an adhesive material only at the points to which the characters are to be attached, molding a paste-like mass to the shape of the characters desired, allowing said molded mass to dry, and utilizing the adhesive material on said receiving surface to withdraw bodily the dried material from the latter, and attach it to said surface.
